US0D1089900S

(12) **United States Design Patent** (10) **Patent No.:** **US D1,089,900 S**
(45) **Date of Patent:** **** Aug. 19, 2025**

(54) **EGG COLLECTION DEVICE**

(71) Applicant: **Zhuanyun Liang**, Jiangmen (CN)

(72) Inventor: **Zhuanyun Liang**, Jiangmen (CN)

(**) Term: **15 Years**

(21) Appl. No.: **29/983,195**

(22) Filed: **Jan. 9, 2025**

(30) **Foreign Application Priority Data**

Oct. 10, 2024 (CN) 202430636774.8

(51) **LOC (15) Cl.** **30-99**

(52) **U.S. Cl.**

USPC **D30/199**

(57) **CLAIM**

The ornamental design for an egg collection device, as shown and described.

DESCRIPTION

FIG. 1 is a front perspective view of an egg collection device, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the egg collection device, which form no part of the claimed design.

1 Claim, 8 Drawing Sheets
